UNITED STATES PATENT OFFICE.

PHILLIP HIEN, OF CHICAGO, ILLINOIS, ASSIGNOR TO DAVID S. WEGG, OF SAME PLACE.

DESIGN FOR A FILLING-BLOCK AND SUPPORT FOR GRAVITY-ACTING DOGS FOR CAR-COUPINGS.

SPECIFICATION forming part of Design No. 33,751, dated December 18, 1900.

Application filed November 24, 1900. Serial No. 37,681. Term of patent 14 years.

To all whom it may concern:

Be it known that I, PHILLIP HIEN, a citizen of the United States, and a resident of Chicago, in the county of Cook and State of Illinois, have invented and produced a new and original Design for a Filling-Block and Support for Gravity-Acting Dogs for Car-Couplers, of which the following is a specification, reference being had to the accompanying drawings, and to the letters of reference marked thereon, which form a part thereof.

In said drawings, Figure 1 is a side elevation of a device embodying my invention. Fig. 2 is a front elevation of the same. Fig. 15 3 is a top plan view of the same. Fig. 4 is an elevation of the side opposite to that shown in Fig. 1.

As shown in said drawings, the leading or material feature of my design consists of a plate A, provided on one edge intermediate of its ends with a projection a, adapted to extend within and fill a groove in a lifting-pin of a car-coupler. Said plate A is materially thicker at its middle portion than at the projection a and is cut away at each end, as indicated in Figs. 1 and 4, to approximately the

same thickness as said projection. A downwardly and obliquely directed lug B is secured integrally on the under side of said plate transversely thereof and integral with the same and the projection a, as clearly shown in Fig. 2 and as indicated in dotted lines in Fig. 3. Said lug B at a point approximately beneath said plate A is provided with a cylindric aperture extending therethrough parallel with said plate and adapted to afford means for pivoting thereon within the coupler-head a gravity-acting dog.

Having described my invention, what I claim as new, and desire to secure by Letters Patent, is—

The design for a filling-block and support for gravity-acting dogs for car-couplers, substantially as described.

In testimony whereof I have hereunto subscribed my name in the presence of two witnesses.

PHILLIP HIEN.
